TOOLHEAD RETAINER.

Swan Norman Rosengren, Seattle, Wash.

Application March 9, 1946, Serial No. 653,280

5 Claims. (Cl. 306—32)

1

The tool head retainer of this invention may be utilized for retaining on a handle any kind of a tool head having a bore through which the handle end projects. Examples of such tools are hatchets, axes, pickaxes, mattocks, hand hammers of various types, sledge hammers, mallets, grub hoes, adzes, shake-splitting froes, brush hooks, scythes, etc. In some of these tools the end of the handle which carries the tool head tapers toward the extremity of such end, and in other instances the end portion of the handle within the tool head tapers away from the extremity of such end. My retainer is adapted to secure in position tool heads on both types of handle.

While my tool head retainer is of extremely simple construction, it acts to hold the tool head in place positively. Despite the effectiveness of its action, the retainer may be manipulated readily to release the tool head for removal from the handle, unless the retainer has been specially secured to prevent such quick release operation.

Not only is the retainer itself of simple construction, but little special work is required on the tool handle to accommodate the retainer, and no change in the structure of conventional tool heads is necessary for utilization of the retainer.

Because of the wide variety of tools with which my retainer may be employed, I have selected only one representative type for illustration in the drawings, namely, a pickaxe. It will be understood, however, from such illustrations, how the retainer may be applied to tools of other types. Certain of the forms of retainer illustrated will be more suitable for one type of tool than for another, and for some tools it may be desirable to modify even the illustrative forms of retainer shown in the drawings while utilizing the principles of my invention as defined in the appended claims.

Figure 1 is a perspective view of a pickaxe head and handle employing a different type of retainer. Figure 2 is a sectional view through the pickaxe head and handle taken along line 10—10 of Figure 1. Figure 3 is a side elevational view of a portion of the pickaxe head and handle showing my retainer.

Figure 4 is a view similar to Figure 2 showing a pickaxe head in section and a portion of the pickaxe handle in elevation, to which a different form of retainer, illustrated partially in section and partially in elevation, is applied. Figure 5 is a perspective view of the retainer shown in Figure 4.

Figure 6 is a side elevational view of a portion

2

of a pickaxe head and handle illustrating still a different form of retainer.

The essential characteristic of all of the various forms of my tool head retainer shown in the drawings is that one portion of the retainer engages the handle to prevent movement of the retainer in one direction along the handle, and another portion engages an edge of the tool head to prevent its movement relative to the retainer in the same direction lengthwise of the handle. Most of the modifications of the retainer are generally U-shaped. The formation of the legs of the retainer, the portion connecting the legs, and the tips of the legs varies from one modification to another depending upon the particular application of the retainer.

Retainers following the principles of the invention may be utilized for retaining heads on handles the head-receiving portions of which taper away from the extremity of the head-receiving end. Thus in the case of the pickaxe shown in Figure 1, the tool head-receiving portion of the handle 3 tapers away from the extremity 30 of the handle. Such tapered shape is seen better in Figure 2. Since the handle-receiving aperture in the head H' is tapered substantially complementally to the taper of the handle, the head cannot fly off. The head can, however, work toward the end of the handle 30 grasped by the workman, which is annoying.

The handle 3 shown in Figure 2 has an aperture 30 extending through it, which preferably is reinforced by a bushing 31. Through this hole extends a U-shaped retainer, including legs 4, and a linear leg-connecting portion 20 passing through the handle aperture. The tips of the legs 4 are bent to form lugs 41, which in this instance abut the edge of the head H' adjacent to the handle aperture 30 and the handle-anchored portion 20 of the retainer, instead of the edge of such head remote from this aperture. In effect, therefore, the legs 4 of the retainer serve as struts, being stressed lengthwise in compression, instead of in tension as are the legs of the retainers described above.

When the type of retainer shown in Figure 2 is employed, again the tool head is placed on the handle in the conventional fashion before the retainer is applied. One leg 4 of the retainer is then inserted through the handle hole 30 and the legs 4 are swung into the position of Figure 2 with their tips abutting the head. In order to maintain them in such position it is preferred that the leg tips be bent toward each other to form lugs 41 which are pointed so that they can

be driven somewhat into the wood of the handle in the manner shown.

The modified type of retainer shown in Figure 3 includes a leg 4 and a linear leg-connecting portion 40 which passes through a hole 30 in the handle. In this instance the tip of the leg is not formed as a lug, but the end of the leg abuts the adjacent edge of the tool head H'. To prevent the legs 4 from swinging out of the retaining position shown in solid lines to the broken line position, a binding wire 42 may be wrapped a few times around the handle and its ends twisted together. Such a retainer may have either two legs 4, one at each side of the handle, or only a single leg. In the latter instance the binding wire 42 not only will prevent the leg from swinging or moving away from the handle 3 out of contact with the tool head, but will maintain the handle-anchored portion 40 of the retainer engaged in the aperture 30, even though it has no hook or other projection on its end opposite leg 4.

Like the retainer of Figure 3, that shown in Figure 4 incorporates a leg or legs 4 which have no lugs at their tips, such tips merely abutting directly the adjacent edge of tool head H'. In this instance, however, the handle-anchored portion of the retainer is not linear but constitutes a coil. The handle, therefore, does not have an aperture through it, as do the handles of Figures 2 and 3, but is provided with a groove 32 adapted to receive the coil portion of the retainer.

The retainer of Figure 4 may be applied either by wrapping its coil portion 43 around the handle in its groove 32, or by precoiling this portion in the form shown in Figure 5 and then expanding it somewhat to apply it to the handle. When the retainer utilizes a coil portion to anchor it to the handle, such portion will prevent appreciable tilting of legs 4 in any direction, so that it probably will not be necessary to provide a binding wire such as the wire 42 shown in Figure 3, whether the retainer has two legs or only one leg.

The retainer of Figure 6 is precisely the same as that shown in Figures 4 and 5, except that the tips of the legs 4 are formed with a special type of lug for engaging the tool head. In this instance in order to hold the tool head tightly upon the handle the retainer does not form simple abutment surfaces, but instead the lugs 44 are in the form of coils disposed with their axes perpendicular to the legs 4. Such lugs are therefore resilient, and continuously exert a pressure against the tool head tending to force it into more firm engagement with the tapered surface of the handle. Except for this resilient feature it will be evident that the retainer of Figure 6 operates much like the retainer of Figure 4, and may be applied to the handle 3 in a similar fashion.

I claim as my invention:

1. A retainer for securing a handle within the aperture of a tool head, comprising a member including a leg portion, and a portion integral with said leg portion, extending transversely thereof,

and in anchoring engagement with the tool handle to prevent movement of said leg portion in one direction lengthwise of the handle, the tip of said leg portion abutting the edge of the tool head adjacent to said transverse portion to prevent movement of the tool head relative to said leg portion lengthwise of the handle in said one direction.

2. A retainer for securing a handle within the aperture of a tool head, comprising a member including a leg portion extending lengthwise of the handle and exteriorly thereof, and a portion integral with said leg portion, extending transversely thereof, and in anchoring engagement with the tool handle to prevent movement of said leg portion in one direction lengthwise of the handle, the tip of said leg portion abutting the edge of the tool head adjacent to said transverse portion to prevent movement of the tool head relative to said leg portion lengthwise of the handle in said one direction.

3. A retainer for securing a handle within the aperture of a tool head, comprising a member including a pair of leg portions disposed on opposite sides of the handle and extending lengthwise thereof, and a portion integral with said leg portion, extending transversely thereof and in anchoring engagement with the tool handle to prevent movement of said leg portions in one direction lengthwise of the handle, the tips of said leg portions abutting the edge of the tool head adjacent to said transverse portion to prevent movement of the tool head relative to said leg portions lengthwise of the handle in said one direction.

35 4. The retainer as defined in claim 3, in which the handle is apertured and the transversely extending portion of the member in anchoring engagement with the handle extends through such aperture.

40 5. The retainer as defined in claim 3, in which the handle is notched and the transversely extending portion of the member formed integrally with the leg portions comprises a coil encircling the handle and received in the notch to provide 45 anchoring engagement of such portion with the tool handle.
